UNITED STATES PATENT OFFICE

2,133,194

TOY

Ernst Horn, Nuremberg, Germany

Application April 9, 1938, Serial No. 201,148
In Germany March 1, 1938

6 Claims. (Cl. 46—210)

This invention relates to toys, and more particularly to toys representing the automobile traffic taking place at street-crossings of cities and the mode of supervising and controlling said traffic.

My present invention relates to an improved and simplified construction of the toy described and claimed in the U. S. Patent No. 2,103,447 granted to Ludwig Carl of Nuremberg, Germany. The toy described and claimed in the said patent consists essentially of a base plate having two streets crossing each other and comprising guide-grooves adapted to guide toy-vehicles travelling therein and stops or pins co-operating with said guide-grooves, said stops or pins being adapted to be raised and lowered in pairs within said guide-grooves to stop the travel of said vehicle or to permit free passage thereof, respectively.

In contra-distinction to the toy described and claimed in the aforesaid U. S. patent, in which toy an electric lamp supplied with current from a small battery serves to indicate at a time the direction in which a toy vehicle may travel on one of said streets, while the supply of current for said lamp is controlled by switching means in the form of a control disk, my present invention consists essentially therein that a mechanically adjustable direction indicator is connected with the toy, said indicator being operated or controlled by means of said control disk serving for the control of said stops or pins in order to adjust said indicator in a position indicating the street or guide-groove which at a time is free for the passage of a toy vehicle therethrough.

My present invention will represent an improvement in so far as a toy of the present kind may be operated without said electric lamp and said battery forming part of the construction according the aforesaid U. S. patent. The direction indicator forming part of my present invention, in addition, will always be effective and in condition ready to operate and particularly avoids eventual failure of the electric lamp due to exhaustion of the battery supplying current thereto.

Moreover, by adjusting said direction indicator mechanically by means of said control disk according to my invention, any failure of said electric lamp or battery will be positively avoided by mechanically adjusting said direction indicator and imparting thereto a proper turning motion into the direction of the street which at a time is free for passage of a toy-vehicle.

In the accompanying drawing I have repre-

sented an example of construction of my improved toy.

Fig. 1 being a top-view taken on the base-plate of the toy, and

Fig. 2 a cross-section along line I—I of Fig. 1.

Referring more particularly to the drawing, the base-plate 1 of the toy is provided with two crossing streets, either street comprising a number of guide-grooves 2, 3 and 5 which partly intersect each other and partly merge one into another. Said streets or guide-grooves may also be connected with each other by switching tongues provided in depressions 6. For either street there are provided in the base-plate 1 in front of the crossing oppositely positioned stops or pins 8 which may be raised and lowered. Said stops or pins 8 are furthermore mounted on resilient tongues 9, 10 which may be commonly and positively adjusted in pairs by means of four oblique surfaces 12 of a control-disk 11 provided with an operating lever or handle 14, 15 permitting two oppositely positioned stops or pins 8 to be raised and lowered at a time. Said stops or pins 8 in raised position will lock the street or guide-groove, while in lowered position they will unlock the second street or guide-groove which is directed at an angle with respect to said first street or guide-groove.

In order to indicate the street or guide-groove at a time unlocked by said stops or pins 8 according to my present invention I provide a mechanically adjustable direction indicator on the base-plate 1 of the toy, said indicator being controlled and operated by means of said control-disk 11 in a way to indicate the street or guide-groove which at a time is free for passage of a toy-vehicle.

Said direction indicator preferably is of the form of a human figure representing a traffic control man and detachably mounted on a shaft which is preferably provided with a square head 13, said shaft passing freely through said control disk 11 and being located above the crossing which is formed by said streets on said base-plate.

At its under end said shaft carries a gear-wheel 16 being in mesh with the teeth on a segmental arm 17 which is mounted on the base-plate 1 to swing about the point 4. A pin 18 provided on said control disk 11 extends through an aperture in said segmental arm 17 and imparts swinging motion to the latter, as soon as the control disk 11 is rotated by way of the gear-wheel 16, thus effecting rotation of said shaft and therewith of said direction indicator through 45

an angle of ninety degrees, so that the latter is adjusted into the direction of a street or guide-groove at a time free for passage of a toy-vehicle due to the lowered position of the respective stops or pins 8. The toy-vehicle 19 which grips by means of its slide-pins 20 into one of the guide-grooves 2, 3 or 5 of the base-plate 1 will now be free to enter the respective street or guide-groove in the direction indicated by said indicator, while 10 said vehicle will be prevented against entering a street or guide-groove which at a time is locked by said stops or pins 8 when in raised condition.

Instead of the segmental arm 17 and the gear-wheel 16, other operating or motion transmitting 15 means may be employed for imparting a turning to said direction indicator from said control disk 11.

The direction indicator described hereinabove and represented in the drawing in connection 20 with a specific form of traffic toy may also be used in connection with traffic toys of other construction without departing from the principles of my present invention or sacrificing any of its advantages.

I claim:

1. A traffic toy of the character described, said toy having crossing streets consisting of guide-grooves, stopping devices adapted to stop a toy 30 vehicle travelling on one of said streets or guide-grooves at the crossings thereof, control means for said stopping devices, and a direction indicator co-operative with said control means, said direction indicator adapted to be adjusted into the

direction of a street or guide-groove at a time free for passage of said vehicle.

2. A toy as specified by claim 1, said direction indicator located at a crossing of said streets or guide-grooves and mounted detachably on a rotatable shaft, said shaft being operatively connected with said control means.

3. A toy as specified by claim 1, said direction indicator located at a crossing of said streets or 10 guide-grooves and mounted detachably on a rotatable shaft, and motion transmitting means interposed between said control means and said shaft.

4. A toy as specified by claim 1, said direction indicator located at a crossing of said streets or 15 guide-grooves and mounted detachably on a rotatable shaft, a gear-wheel mounted on said shaft, a segmental arm in mesh with said gear-wheel, a pin on said control means extending through an aperture in said segmental arm.

5. A toy as specified by claim 1, said direction indicator being of the form of a human figure, such as a traffic control man, mounted on a rotatable shaft, said shaft being operatively connected with said control means.

6. A traffic toy of the character described, said toy having two crossing streets, stopping devices adapted to lock passage of a toy vehicle through one or the other of said streets, control means for said stopping devices, and a mechanical direction indicator co-operative with said control means and adapted to indicate the street at a time free for passage of a toy-vehicle therethrough.

ERNST HORN.
